MAGAZINE OR PHONOGRAPH RECORD RACK
OR THE LIKE

Joseph H. Fox, New York, N. Y.

Application October 25, 1955, Serial No. 38,564

Term of patent 3½ years

(Cl. D33—2)

Fig. 1 is a perspective view of a magazine or phonograph record rack or the like embodying my new design; and

Fig. 2 is a similar view showing parts of the same in separated relation.

I claim:

The ornamental design for a magazine or phonograph record rack or the like, substantially as shown.
